(57) **CLAIM**

The ornamental design for a syringe pump, as shown and described.

DESCRIPTION

FIG. 1 is a perspective view of a syringe pump;

FIG. 2 is a front view thereof;

FIG. 3 is a rear view thereof;

FIG. 4 is a left side view thereof;

FIG. 5 is a right side view thereof;

FIG. 6 is a front view thereof in an alternate state; and,

FIG. 7 is a front view thereof in another alternate state. The broken lines in the drawings depict portions of the syringe pump that form no part of the claimed design.
